METHOD OF MAKING ARC EXTINGUISHING SLEEVE
Samuel M. Shobert, R.R. 2, Ireland Road,
Mishawaka, Ind.
Filed July 17, 1961, Ser. No. 124,733
4 Claims. (Cl. 29—155.5)

This invention relates generally to arc extinguishing devices, and more particularly to a replaceable fuse holder and the method of making the same.

A common type of circuit interrupting device for use in electrical circuits is the replaceable fuse. These fuses conventionally comprise a replaceable fuseable element removably inserted in a sleeve or tube of insulating material. In the past, such tubes have comprised an inner sleeve adjacent the arc formed of bone fiber with an outer covering of laminated phenolic paper. Bone fiber has been employed since it will not support combustion and yet evolves gases when exposed to an electric arc which extinguish the arc. Bone fiber however is too unstable to permit use by itself since it readily absorbs water and loses dimensional stability and thus the bone fiber sleeve must be supported by some other non-conducting material. Further, the gases which are evolved from the bone fiber are confined in a relatively small space thus generating high pressures and the bone fiber alone does not possess the requisite strength to withstand such pressures. Additionally, bone fiber is expensive, difficult to make and difficult to work with.

While the aforementioned fuse tube employing an inner bone fiber sleeve and an outer covering of laminated phenolic paper has been used for many years, it nevertheless has had relatively low bursting strength since the paper covering was not sufficiently strong. However, difficulties have been encountered in attempting to provide a different covering to bond to the bone fiber and which was sufficiently strong to overcome its dimensional instability. It is therefore desirable to provide a refusible fuse tube having the requisite arc extinguishing properties and increased bursting strength which can be more economically manufactured than prior fuse tubes known to the present applicant.

It has been discovered that boric acid possesses very much the same arc extinguishing properties as bone fiber. Boric acid in powdered form is cheap and readily available, however, in order to employ it in a fuse tube, it is necessary to form it into a sleeve and to cover it with an outer covering possessing the requisite bursting strength. My invention in its broader aspects, therefore, provides an arc confining and extinguishing sleeve comprising an inner sleeve formed of boric acid having glass threads braided on its outer surface, the threads being impregnated in hardened and cured resin thereby forming an outer sleeve bonded to the inner sleeve.

It is an object of my invention to provide an improved arc extinguishing device.

Another object of my invention is to provide an improved refusible fuse tube having arc extinguishing properties and high bursting strength.

A further object of my invention is to provide an improved method of making an arc extinguishing device.

A still further object of my invention is to provide improved method of making a refusible fuse tube.

Further objects and advantages of my invention will become apparent by reference to the following description and the accompanying drawing, and the feature of novelty which characterize my invention will be pointed out with particularity in the claims annexed to and forming a part of this specification.

2

In the drawings:
FIG. 1 is a side view, partly in cross-section and partly broken away, showing a fuse incorporating the improved refusible fuse tube of my invention; and

5 FIGS. 2 through 8 inclusive schematically illustrate the steps involved in practicing the method of my invention.

Referring now to FIG. 1 of the drawing, there is shown a fuse, generally indicated at 10, comprising an elongated inner cylindrical sleeve 12 formed of compressed boric acid powder. Inner sleeve 12 has a coaxial opening 14 formed therethrough for accommodating the fusible element as will be hereinafter more fully described. A plurality of glass threads are helically braided on the outer surface of the sleeve 12, the threads being impregnated in 10 and the outer surface of the sleeve 12 being coated with hardened and cured resin to form an outer sleeve or covering 16 bonded to the inner sleeve 12. The outer 15 surface of the outer sleeve is preferably polished.

While suitable dimensioning of the glass threads forming the braid and suitable resins are well known in the fiber glass-resin art, I prefer to employ threads of the glass yarn type, each thread being composed of a multiplicity of tiny elongated fibers which, in effect when bundled together form a final continuous length of thread. I further 20 prefer to employ thermo-setting resins of the polyester, polyvinyl or epoxy type.

The upper end 18 of the outer sleeve 16 is suitably threaded and interiorly threaded metallic contact element 20 is removably secured thereto, as shown, thereby 25 closing the upper end of the central opening 14. Inserted within the central opening 14 is a replaceable fuse link 22 having one end 28 electrically connected to the contact element 20 and its other end 30 connected to an electrical lead 24 which extends out of the other end of the fuse 30 holder and is connected to another contact element 26 in accordance with conventional practice. It will be readily seen that when the contacts 20 and 26 are connected in an electrical circuit, the fusible link forms a part of the 35 circuit and current will flow therethrough. When a predetermined excessive current flows through the fusible link 22 it will be ruptured and an electrical arc will be established between the two terminals 28 and 30 connected to the respective ends of the fusible link 22. The presence of this arc within the central opening 14 of the boric acid sleeve 12 will cause the evolution of arc-extinguishing gases. It will further be readily seen that the 40 high pressure gases which are generated within the central opening 14 subject the inner sleeve 22 to very stresses. However, such stresses are resisted by the helical braid and its cured resin impregnation forming the outer covering 16 thus substantially increasing the bursting strength 45 of my improved fuse holder over that provided by prior fuse holders known to the present applicant.

Referring now to FIGS. 2 through 8 inclusive, in accordance with the method of my invention, an elongated cylindrical steel mandrel 32 is disposed coaxially within an elongated hollow cylindrical container 34 and extending snugly through opening 36 in bottom wall 38 thereof, as shown. Commercial grade boric acid powder is then 50 poured into the open end 40 of container 34 substantially to the top thereof so as to surround the mandrel 32. It will be readily understood that the mandrel 32 is proportioned to provide center opening 14 in sleeve 12 of the desired diameter and the inner wall of container 34 55 is spaced from the mandrel 32 by a radial distance sufficient to provide the desired wall thickness of the sleeve 12 for the requisite voltage capacity of the finished fuse tube.

A suitable plunger 42 is then positioned over the upper 60 end of mandrel 32, as shown in FIG. 3, and is moved downwardly in the direction shown by the arrow 44 so as to compact the boric acid powder within the container 34 and around the mandrel 32.

The cylinder 34 is then removed from the mandrel 32 leaving the resulting sleeve 12 of compressed boric acid on the mandrel 32, as shown in FIG. 4. A cake of compressed boric acid powder is itself fragile, however, I have found that when the boric acid powder is compressed and compacted around the steel mandrel 32, it is self supporting and readily handled since the steel mandrel imparts strength to the body.

Referring now specifically to FIG. 5, the sleeve 12 of compacted boric acid powder on the mandrel 32 then has a helical braid 46 of glass threads formed thereon by means of a conventional commercially available braiding machine 48. This machine comprises a rotatable supporting table 50 on which a suitable number of spools 52 of glass thread or strands are supported. Each of the spools 52 is rotatably mounted on a spindle 54 which has its lower end seated in the usual serpentine or undulating grooves 55 of the table 50, as well known to those skilled in the art. The inner sleeve 12 on the mandrel 32 has the threads from the spools 52 secured to its upper end 56 and is then moved upwardly through center opening 58 in table 50 of braiding machine 48 in the direction shown by the arrow 60 as the table is rotated thereby to move the spools 52 in the grooves 55 in table 50 to form the helical braid 46. Braiding machines and their mode of operation are well known to those skilled in the art and thus it is unnecessary further to describe the braiding machine 48.

After the braid 46 has been formed on the outer surface of the sleeve 12, the resulting assembly is then immersed or wetted by some suitable means, as by being dipped in a tank 62 of suitable catalyzed resin, as shown in FIG. 6 and as well known in the glass fiber-reinforced resin art. It is important to insure that all of the strands forming the braid are thoroughly impregnated with the resin and further to insure that a sufficiently thick layer of resin is formed over the braid 46 completely coating the same and bonded to the outer surface of the sleeve 12.

The compressed boric acid sleeve 12 with the braid 46 thereon impregnated with resin, as above described and still on the mandrel 32 is then placed in a curing mold 64. This mold is heated by the use of steam or any other heating medium, until the resinous material is completely cured, the temperature and time of curing depending of course, on the particular resin employed.

The resulting assembly is then removed from the mold 64, the steel mandrel 32 is removed, and the outer surface of the resulting outer covering 16 may then be ground smooth, as shown in FIG. 8.

It will be seen that with removal of the steel mandrel, the inner sleeve 12 of compressed boric acid powder is provided for accommodating the fuse link 22 and it will be seen further that the provision of the helical braid of glass fibers impregnated and bonded to each other and to the sleeve 12 stabilizes the compressed boric acid sleeve and gives it excellent dimensional stability and greatly improved bursting strength properties.

While I have illustrated and described specific embodiments of my improved replaceable fuse tube and method of making the same, further modifications and improvements will occur to those skilled in the art and I desire therefore in the appended claims to cover all modifica-

tions which do not depart from the spirit and scope of my invention.

What is claimed is:

1. The method of making an arc confining and extinguishing sleeve comprising the steps of: forming an elongated inner sleeve of boric acid powder about a supporting mandrel and compressing said powder into tightly compacted form; forming a braid of glass threads on the outer surface of said sleeve; impregnating said braid with a resin material; curing said resin to bond the threads of said braid together and to said inner sleeve; and removing said mandrel from said inner sleeve.
2. The method of making a refusible fuse holder comprising the steps of placing an elongated cylindrical supporting mandrel coaxially in an elongated cylindrical mold having a closed lower end and an open upper end; pouring boric acid powder into said mold around said mandrel; compressing said powder in said mold around said mandrel to form a tightly compacted inner sleeve; removing said mandrel from said mold with said sleeve thereon forming a helical braid of glass threads on the outer surface of said inner sleeve; impregnating said braid with a resin material; curing said resin to bond the threads of said braid together and to said inner sleeve; and removing said mandrel from said inner sleeve.
3. The method of making a refusible fuse holder comprising the steps of: placing an elongated cylindrical supporting mandrel coaxially in an elongated cylindrical mold having a closed lower end and an open upper end; pouring boric acid powder into said mold around said mandrel; compressing said powder in said mold around said mandrel to form a tightly compacted inner sleeve; removing said mandrel from said mold with said sleeve thereon; forming a helical braid of glass threads on the outer surface of said inner sleeve; dipping said mandrel with said inner sleeve and braid thereon in a bath of resin material thereby to impregnate said braid; placing said mandrel with said inner sleeve and impregnated braid thereon in a heated mold to cure said resin thereby to bond said threads together and to said inner sleeve; and removing said mandrel from said inner sleeve.
4. The method of claim 3 further comprising the steps of working the outer surface of said bonded threads to render said holder smooth.
